Fig. 1

Fig.2

Fig.3

FIGURE 1 is a perspective view of the combination fuel dispensing and product storage, display and dispensing unit illustrating one side and one end and showing my new design.

FIGURE 2 is a side elevation of the design shown in FIGURE 1.

FIGURE 3 is an end elevation of the design shown in FIGURE 1 with the hose and nozzle portion omitted.

The opposite side and end of the unit, not shown, are substantially the same as the corresponding side and end which are shown.

I claim:

The ornamental design for a combination fuel dispensing and product storage, display and dispensing unit, substantially as shown and described.
